(57) **CLAIM**

The ornamental design for a TV receiver, as shown and described.

DESCRIPTION

FIG. 1 is a front, right side, perspective view of a TV receiver showing our new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is an enlarged view thereof;

FIG. 9 shows the TV receiver in an alternate position;

FIG. 10 is an alternate view thereof; and,

FIG. 11 is a second alternate view thereof.

The broken lines indicate portions of the article that form no part of the claimed design.

1 Claim, 11 Drawing Sheets
